METHOD OF FORMING A LIGHT DIFFUSING ELEMENT

John Frei, Jr., Chicago, Ill., assignor to The Glo-lite Corporation, Chicago, Ill., a corporation of Illinois

Application April 8, 1936, Serial No. 73,208
Renewed July 24, 1939

1 Claim. (Cl. 49—85)

My invention relates to light transmitting and diffusing elements and to the method of production thereof.

More specifically the present invention has for its principal object the provision of a new and improved method of forming the light diffusing element integrally with the light transmitting element.

Other features and advantages of the invention will appear from the following detailed description, when taken in connection with the accompanying drawing, in which:

Figure 1 is a fragmentary elevational view of a light transmitting element adapted to have a light diffusing element formed integrally therewith;

Figure 2 is a diagrammatic view showing the application of heat to one end of the light transmitting element of Figure 1, as one of the steps 20 in the method of forming the light diffusing element integrally with the light transmitting element;

Figure 3 is a side elevational view of a form of mold or press adapted to embrace one end of the light transmitting element, as another step in the method of forming the light diffusing element therewith;

Figure 4 is a fragmentary front elevational view, on an enlarged scale, of a light transmitting and diffusing element embodying the principles of the present invention;

Figure 5 is a vertical sectional view taken substantially along the line 5—5 of Figure 4; and

Figure 6 is a diagrammatic view showing one method of providing a diffusing surface on the light diffusing element.

Referring now in detail to the drawing, it is known that light rays suitably introduced into one end of a glass rod will be transmitted longitudinally therethrough and will illuminate an object at the other end thereof when such object is translucent, as by being ground or frosted, to render it light diffusing. To practice my invention, therefore, I first take a glass rod 7 and cut it to its required length. This rod may be formed of ordinary commercial glass, and it is of substantially constant diameter throughout its length.

As shown in Figure 2, one end of this rod is then inserted into a flame 8, or subjected to heat in some other known or preferred manner, to form a globule or mass of plastic glass 9, at such end of the rod. While the globule of glass is still

in a plastic condition, it is inserted into a mold or press 10, which mold or press has die surfaces in the form of the object it is desired to form on the end of the rod. Closing of the mold will serve to engage the die surfaces thereof with the 5 globule; and thereby form it into the desired object.

Mold 10 may be of any suitable or preferred form. In the form shown, it consists simply of an upper section 11 and a lower section 12. These 10 sections are hinged together as indicated at 13, and the upper section is provided with a handle 14 for moving such section relatively to the lower section. Preferably, the actual die of the mold, as indicated by the dotted lines 15, is split 15 substantially centrally thereof, one half being carried by the upper mold section 11, and the other half being carried by the lower mold section 12. This assures that the object formed on the end of the rod will have its center, indicated at 16, disposed at some point on the axis of the rod, as indicated by the line A—A in Figure 5. As stated, the die of the mold will, of course, have the configuration of the object to be formed. In the embodiment shown, the object 20 is star-shaped, as indicated at 17.

The rod 7 is permitted to remain in the mold until the object, being formed in the plastic glass thereon, has cooled sufficiently to enable it to retain the desired shape. After removal from 30 the mold, the object then has its surfaces ground or sand-blasted, or otherwise treated, to render it light diffusing. As indicated in Figure 6, the object may, if desired, be dipped into a tank 18 containing a suitable known frosting 35 liquid 19 therein, which liquid deposits a light diffusing coating on the object. This latter method of rendering the object light diffusing is preferable, as it is more rapid and convenient.

Having thus described the invention, what I 40 claim is:

The method of forming a light diffusing object on one end of a solid glass rod whereby rays of light transmitted axially through said rod will be diffused by said object which comprises the 45 following steps: forming a coherent solid plastic mass of glass on one end of the rod by the application of heat only, inserting said glass mass into a mold, pressing the object in its desired form from said mass, cooling the object so formed, and 50 providing said cooled object with a light diffusing surface.
